2,521,554

METHOD OF MAKING PAPER-COVERED VENEER

Richard N. Ware, Jr., and Reginald Cannon, Tallulah, La., assignors to Chicago Mill and Lumber Company, Chicago, Ill., a corporation of Delaware

Application July 16, 1947, Serial No. 761,188

3 Claims. (Cl. 154—132)

1

This invention relates to the production of paper covered wood veneer from green, undried, steamed wood and moistened, stretched paper, and specifically deals with a process of making veneer products involving the reeling into rolls of freshly peeled veneer sheets, the steaming of said rolls, the unreeling of the hot steamed rolls into elongated flat ribbons of veneer, and the covering of the ribbons with adhesive-coated stretched paper which is fixedly united to the wood to hold it in an expanded condition as it is dried.

This application is a continuation in part of our copending application Serial No. 617,244 entitled: "Method and Apparatus for Making Paper Covered Veneer," filed September 19, 1945, now U. S. Patent 2,425,660 granted August 12, 1947.

In our aforesaid parent application, Serial No. 617,244, freshly peeled veneer sheets are stapled together to form an endless ribbon and the endless ribbon is then covered with adhesive coated wet stretched paper.

According to the present invention, freshly peeled veneer is wound into relatively tight rolls. These rolls are heated with wet steam to raise their temperature without drying the wood. The logs from which the wood is peeled are in a green, undried condition. The hot steamed rolls of veneer are unreeled as needed to form ribbons. The ribbons of each successive roll are stitched together in end to end relation to form a continuous ribbon. The continuous ribbon, while still in a hot condition, is advanced between the adhesive-coated faces of wet stretched paper webs. The adhesive on the stretched paper webs is of a type adapted to sufficiently bond the paper to the wood so that relative slippage therebetween cannot occur even before the wood and paper are dried. The bond thus created is sufficiently strong so that the paper will hold the wood against shrinkage during a subsequent drying operation. At the same time the relatively small degree of shrinkage occurring during the drying operation will not cause a puckering or wrinkling of the paper because it is in a stretched condition and has substantially the same coefficient of shrinkage as the wood that is bonded thereto.

An important feature of the present invention resides in reeling of the freshly peeled veneer sheets so that they can be handled in rolled-up form.

Another feature of the invention resides in the wet steaming of the veneer reel to uniformly heat the wood for producing a hot veneer that will speed up subsequent setting and drying. We have found that certain species of wood, such as cottonwood, cannot be satisfactorily peeled into veneer sheets from heated logs because the wood fibers fuzz up when lathe cut in a hot condition.

2

According to the present process, the logs are peeled in a cold condition but the freshly peeled veneer is heated.

Another object of the invention is to provide a process of making paper covered veneer which is faster in operation than the process disclosed in our parent application Serial No. 617,244.

Another object of the invention is to provide a method of making paper covered veneer wherein the veneer is steam heated and receives the paper coverings while it is in a hot condition for speeding up the drying of the adhesive.

A still further object of the invention is to provide a continuous process of making a veneer product wherein freshly peeled veneer sheets are wound into rolls if relatively long, or are stitched together if relatively short, and are eventually formed into a continuous ribbon.

Other and further objects of this invention will be apparent to those skilled in the art from the following detailed description of the annexed sheets of drawings which, by way of a preferred example, illustrate one embodiment of the invention.

25 On the drawings:

Figure 1 is a fragmentary broken diagrammatic side elevational view of the first portion of the apparatus used for the method of this invention for forming rolls of veneer for steaming the wound veneer rolls, and for unreeling the wound steamed rolls.

Figure 2 is a view similar to Figure 1 but illustrating a successive portion of the apparatus including the structure for covering the wood veneer with paper.

Figure 3 is a view similar to Figures 1 and 2 but illustrating the third or last portion of the apparatus which serves to dry the paper covered veneer product.

Figure 4 is a plan view of a veneer sheet, one-half of which is covered with paper in accordance with this invention, and illustrating the manner in which the paper holds the wood against shrinkage.

Figure 5 is a cross-sectional view taken along the line V—V of Figure 4.

Figure 6 is an elevational view of a wound roll of veneer on a shaft equipped with end wheels or guide rollers for riding on the rails of the apparatus of Figure 1.

Figure 7 is a transverse cross-sectional view taken along the line VII—VII of Figure 6.

Figure 8 is a somewhat diagrammatic cross-sectional view taken either along the line VIII—VIII of Figure 1, or the line VIII—VIII of Figure 2 and showing the stitching machines used in the apparatus.

Figure 9 is a fragmentary plan view showing adjoining stitched-together veneer sheets.

As shown on the drawings:

As shown in Figure 1, the reference numeral 10 designates generally a log-peeling lathe commonly used for cutting veneers from wooden logs. The lathe 10 includes a driven log support 11 and a cutting blade 12. The support 11 drives a log 13 in the direction of the arrow against the blade 12 and a veneer ribbon 14 is peeled or cut from the log. In accordance with this invention a reeling stand 15 is mounted adjacent the lathe 10 and drivingly supports a shaft 16 on which the veneer 14 is reeled to form a roll 17.

Uprights 18 carry three superimposed pairs of tracks or rails 19 to provide a roll-handling stand 20 in front of the reel 15.

The axles or shafts 16 for the rolls 17, as best shown in Figure 6, have flanged rollers 16a on the ends thereof for riding on the tracks 19. The flanges overlie the outsides of the tracks 19 to hold the rolls between the rails.

The reeling stand 15 is adapted to raise a wound roll 17 to the two upper tracks 19 for depositing rolls 17 on these tracks. The rolls are advanced along the stand 20 to a steam chest 21 having inlet doors 22 adapted to be opened to permit entry of the rolls 17 while still supported on the tracks 19. A plurality of rolls are accommodated at the same time in the steam chest 21. A steam inlet pipe 23 supplies wet steam at about 4 to 75 lbs. per square inch pressure to the steam chest 21 for saturating the chest. Wet steam circulates all around the rolls 17 in the steam chest and heats these rolls without drying the veneer. The length of the heat treatment will vary, depending upon the thickness of the veneer and the size of the rolls. It is preferred that the rolls do not exceed 30 inches in diameter and that they be wound tight enough so as to be evenly disposed around the shaft. Under such conditions the steam treatment may vary from 30 minutes to two hours. The temperature of the steam is preferably maintained around 225 to 240° F. The wood becomes heated to less than the temperature of the steam or to about 160 to 225° F.

After the steaming treatment, the shaft rollers 16a are advanced on the rails 19 to carry the wound rolls 17 out through exit doors 24 of the steam chest.

The top rails 19 have spring-pressed or counterweighted end sections 25 pivoted thereon and adapted to mate with a reel support 26 at the end of the reel section 20. A spring 27 or counterweight normally holds the pivoted sections 25 in a raised position to open up a gap 28 between the reel support 26 and the rail section 25. When a roller 16a rides up to the rail sections 25, the weight of the roll 17 will depress the springs or counterweights so that the sections 25 will mate with the reel support 26 and the roll 17 is thereby fed to an unreeling stand designated generally by the numeral 29.

The rails 19 beneath the top rails terminate in pivoted end sections 30 pulled upwardly to the inclined position of Figure 1 by springs such as 31 or counterweights (not shown). When rollers carrying rolls 17 are advanced on the rails 19 to the pivoted sections 30, these sections 30 will be depressed to mate with extension rails 32 of a second unreeling stand 33 and the roll 17 will be deposited into this unreeling stand without lifting it off of the rails.

The unreeling stand 29 has inclined extension rails 34 extending downwardly from the rails 26 thereof to spring-pressed or counterweighted piv-

oted sections 35 held by springs 36 or counterweights (not shown) above the rails 32. When the roll 17 is unwound from a shaft and its rollers in the unreeling stand 29 the rollers can carry the shaft down the inclined rails 34 to the spring-loaded or counterweighted rails 35 whereupon the weight of the shaft will depress these rails into registration with an inclined set of rails 37 communicating at their lower ends with the bottom rails 19. When a roll 17 in the unreeling stand 33 is completely unwound from its shaft, the rollers on this shaft will be guided back along the rails 32 to the inclined rails 37 without interference because the rail sections 30 and 35 will be raised by the springs 31 and 36 to an out of the way position as shown in Figure 1. The shafts 16 are thereby returned along the bottom set of rails 19 to the winding reel stand 15. The two top sets of rails 19 are preferably inclined downwardly toward the reel stands 29 and 33 while the bottom set of rails 19 is preferably inclined downwardly toward the winding reel stand 15 so that the wound rolls 17 will gravitate toward the unreeling stands 29 and 33 while the shafts 16 will gravitate toward the reeling stand 15.

Beneath the bottom rails 19 there is provided a conveyor system for handling short pieces of veneer which are not wound into rolls 17. As shown in Figure 1, an inclined conveyor 38 of the belt or tape type extends from under the lathe knife 12 to a horizontal conveyor 39 beneath the bottom rails 19. This conveyor 39 feeds through a clipper 39a which trims the edges of the veneer pieces to form straight ends. The conveyor 39 discharges into a sewing machine 40. As shown in Figure 8, the sewing machine 40 has a head 41 carrying a plurality of needles 42 at spaced intervals across the width of a veneer sheet 14 fed therethrough. As illustrated in Figure 9, pieces of veneer 14 are stitched together by rows of stitches 43 spaced at intervals across their width. The stitched pieces of veneer 14 can fall by gravity out of the machine 40 to be picked up by an inclined conveyor 44 which raises them to an elongated horizontal conveyor 45. The horizontal conveyor extends to another horizontal conveyor 46 beyond the unreeling stand 29. Alternately, as shown in dotted lines, the stitched together pieces of veneer from the conveyor 44 can be wound into a roll on a reeling stand 45a and moved up to the rails 19 for a steam treatment in chest 21.

A conveyor 47 is provided to receive veneer unwound from a roll 17 on the unreeling stand 29 to convey this veneer to the conveyor 46. Another conveyor 48 is provided to convey veneer unwound from a roll on the unreeling stand 33 to the conveyor 46. Therefore, all veneer sheets are eventually fed to the conveyor 46.

The conveyor 45, as indicated above, receives stitched together short veneer pieces. These stitched-together pieces eventually form a ribbon of appreciable length that can be selectively fed to the conveyor 46 for attachment to the trailing end of a veneer sheet 14 from an unwound roll 17, if desired.

As shown in Figure 2, a second sewing machine 49 similar to the machine 40 of Figure 1 receives the veneer 14 from the conveyor 46 and stitches the various veneer sheets together to form a continuous ribbon irrespective of whether or not these sheets come from a roll 17 or from the conveyor 45. The continuous ribbon is fed to an inclined conveyor 50 onto a horizontal conveyor 51.

The continuous ribbon of veneer 14 on the conveyor 51 is next fed between adhesive coated faces of paper webs in a wet stretched condition. The paper webs are preferably composed of tough kraft paper.

As shown in Figure 2, a roll of paper 52 is mounted above the apparatus for covering the top face of the veneer ribbon. A paper web W from this roll is guided under a guide roll 53 to a wetting roll 54 contacting the under face of the web and rotatably mounted in a suitable coating pan 55. The pan preferably contains water at temperatures around 180° F. Alternately, the pan can contain a water emulsion of a paraffin wax capable of imparting a smooth wax finish on the paper while at the same time having the water thereof penetrate into the paper for wetting it. The wet paper web then passes under a guide roll 56 and is fed to a coating machine having a fountain roll 57 applying a coating of adhesive to the top face of the web opposite the face engaged by the wetting roll 54. The adhesive is of a type capable of creating a firm bond before it is thoroughly dried so that no slippage will occur between the paper and wood as the wood begins to shrink during a drying operation. A vegetable protein glue is suitable.

After receiving the adhesive coating, the web is directed over a guide roll 58 and around a turning roll 59 so that its adhesive-coated face will overlie the top face of the veneer ribbon discharged off of the conveyor 51.

A second roll of paper 60 is mounted beneath the apparatus and feeds a second web W over guide rolls 61 to a turning roll 62 for providing a reverse run of the web over a wetting roll 63 operating in a pan 64 to wet the web with hot water or with a water-wax emulsion as described in connection with the web from the roll 52. The web from the wetting roll 63 then passes around another turning roll 65 to again have its direction of travel reversed. Guide rolls 66 direct the web to a coating apparatus 67 which applies the same type of adhesive to the opposite face of the web as is applied to the other web by the coating apparatus 57. The adhesive-coated web is then passed under a guide roll 68 and around a turning roll 69 which directs the adhesive-coated face of the web under the ribbon of veneer 14 discharged from the conveyor 51.

It will be noted that the web runs between the wetting rolls and the adhesive coating machines are appreciably long so that the water can penetrate into the webs and permit them to stretch. The wet webs are placed under tension by the coating machines 57 and 67 so that the adhesive is applied to the wet webs in a stretched condition on the faces of the webs opposite the faces engaged by the wetting rolls. The adhesive itself preferably has a water base so that the opposite faces of the webs are also wet with water. The runs of the webs beyond the adhesive coating machines are also of considerable length so that further stretching of the webs is possible. The adhesive-coated faces of the webs are guided by the turning rolls 59 and 69 in spaced relation above and below the veneer ribbon fed from the conveyor 51.

The webs with the veneer ribbon therebetween are fed through a first press 70 composed of top and bottom rollers spring loaded toward each other by a spring such as 71. The chamber 72 contains a number of press rolls 73 composed of cooperating top and bottom rolls. The bottom rolls only may be driven with a throw in clutch 75

attachment to permit threading of paper covered veneer through the machine. The chamber also contains a series of driven press rolls 74. Thus, as shown, the last three sets of rolls are positively driven and are spring loaded as at 75 to exert increased pressures on the paper and veneer assembly received therebetween. The press 70 advances the webs and veneer ribbon to the press rolls 74 through the idler rolls 73 and, when the assembly is completely threaded through the rolls 74, the drive on the press 70 is released so that the rolls 74 become the main driving rolls for pulling the paper and veneer through the idler rolls 73. The rollers coat for ironing the paper webs on the wood ribbon sandwiched therebetween to insure a good firm contact to create a thorough adhesive bond. The tension pull established by the rolls 74 keeps the paper webs in stretched condition and the idler rolls 73 maintain somewhat of a dragging action on the paper.

The chamber 72 is heated to temperatures around 120 to 180° F. by a steam coil 76 extending through the chamber. The steam coil heats air in the chamber and the heated air starts to remove some of the moisture from the webs and veneer without, however, drying the veneer to its shrinking point, which is usually below 30% moisture content. Moistened air is exhausted from the chamber by a blower 97.

By the time the paper and veneer reach the discharge end of the chamber 72, the adhesive bond between the paper and the wood is sufficiently strong so that the slippage cannot occur when the wood starts to shrink. While the adhesive may not yet be in its final set state, it is, nevertheless, strong enough to hold the wood in its expanded or swollen condition even when the moisture is dried from the wood and the wood tends to shrink. The heated veneer from the steaming operation is soft and pliable and facilitates drying and setting of the adhesive. The adhesive itself can be applied in a heated condition if desired. The paper, of course, is heated from the application of the hot water or wax emulsion. These heat treatments speed up the operation.

The paper covered wood veneer is deposited on another conveyor 77 as it leaves the chamber 72 and this conveyor feeds a flying shears 78 which cuts the material into the desired length segments. The shears 78 includes a tiltable cutting section 79 rocked by an eccentric 80 so as to move the cutter blades with the advancing material at a correlated speed thereby preventing buckling of the advancing material during the cutting operation.

The cut product is deposited on another conveyor 81.

The conveyor 81, as shown in Fig. 3, discharges to a tipple 82 which selectively supplies superimposed conveyors 83 extending through a drying kiln 84. The kiln 84 is quite long and has a blower 85 mounted on top thereof for receiving air from an inlet duct 86 and discharging the air through a distributor duct 87 to an inlet duct 88 at the discharge end of the kiln. The air and kiln are heated by steam pipes or other heating means (not shown) so that the kiln will have an inlet temperature around 250° F. and an outlet temperature around 375° F. The circulating hot air in the kiln drives the moisture out of the paper and wood to produce the final dried product which still contains enough moisture so that it will not warp when exposed to the atmosphere. The conveyors 83 extend beyond the discharge end of the

kiln so that the product can cool down sufficiently to a temperature convenient for handling.

As explained above, the adhesive bond between the paper and the wood is sufficiently strong in a partially set condition so that relative slippage between the paper and wood will not occur when the wood is dried.

As illustrated in Figures 4 and 5, the product 39 of this invention is composed of a wood veneer core 90, adhesive bonds 91 on each face of the core, and paper covers 92. The wood core 90 is held in an expanded swollen condition such as it assumes when it is saturated with moisture. Even though the moisture content of the product is reduced materially beneath the shrinking point of the wood, the paper is strong enough to hold the wood against shrinking. This is illustrated in Figure 4, wherein only half of the wood is covered with paper. The exposed half 90a is in a shrunken, dried condition, while the covered half 90 is just as dry, but in its original expanded condition. As illustrated, considerable shrinkage normally occurs upon the drying of the wood veneer, and this shrinkage frequently produces checks and cracks 93 between fiber bundles of the wood. A dried veneer sheet is therefore usually full of checks and holes such as 93. The grain 94 of the wood extends longitudinally or across the width of the veneer ribbon and in the drying of the uncovered veneer the pith or soft wood between the harder fiber bundles will tear apart to produce the checks and holes. This condition does not occur in the paper covered portion of the wood, where the grain 94 remains in its expanded condition and the fiber bundles are not allowed to pull the softer pith apart to create open holes or checks.

Some slight shrinkage, in the nature of 1 to 2%, does occur as the green wet wood is dried down to the finished condition wherein its moisture content is about 6 to 12%. This shrinkage takes place without puckering or wrinkling the paper bonded to the wood because the paper is also in a stretched condition and shrinks extensively with the wood. Any shrinkage of the wood thereby merely permits simultaneous shrinkage of the stretched paper which in no event reaches the stage where the paper becomes compressed to wrinkle or pucker.

The paper sheets, by being bonded to the green, undried wood in its swollen condition, with a bond that is strong enough to resist relative slippage between the paper and wood even before the wood is dried, will save as much as 10 to 25% of shrinkage loss heretofore attendant with the drying of wood. The undried green wood contains about 120 to 130% moisture by weight, and this moisture content can be reduced to about 30% by weight before shrinkage of the wood begins.

According to this invention, the adhesive bond is sufficiently set before the wood is reduced to a moisture content of 30% to prevent relative slippage between the paper and the wood when the assembly is dried below 30%. The adhesive thus has a strong wet strength setting capacity.

From the above descriptions it will be understood that the invention provides a rapid process of forming paper covered wood veneer including the reeling of veneer sheets into rolls, the steaming of the rolls to uniformly heat the veneer sheets, the covering of the hot veneer sheets with heated moisture-saturated stretched paper, the bonding of the paper to the veneer sheets before

the veneer is dried to its shrinking point and the final drying of the paper covered product to a moisture content between 6 and 12% where it will not warp in any atmosphere.

It will, of course, be understood that various details of the process may be varied through a wide range without departing from the principles of this invention and it is, therefore, not the purpose to limit the patent granted hereon otherwise than necessitated by the scope of the appended claims.

We claim as our invention:

1. The method of making paper covered wood veneer which comprises wet steaming a wound wood veneer roll to heat the wood without drying it, unwinding the hot steamed veneer from the wood, advancing the unwound hot steamed veneer between the adhesive coated faces of two sheets of wet stretched kraft paper, pressing the adhesive coated faces of the paper against the hot steamed veneer as it advances, passing the advancing assembly through a heated chamber to partially set the adhesive for forming a non-slipping bond between the wood and paper without drying the wood to its shrinking point, and drying the paper covered veneer to a moisture content between 6% to 12% while the adhesive bond holds the wood in its expanded swollen wet condition.

2. The method of making paper covered veneer which comprises wet steaming a wood veneer ribbon, wetting one face of each of two webs of paper, stretching said wet webs, applying wet adhesive on the surfaces of said stretched webs, pressing the adhesived surfaces of said webs against opposite sides of said veneer, heating the assembly to bond the paper to the veneer without materially drying the wood, and thereafter drying the assembly to a moisture content below the shrinkage point of the wood while the paper holds the wood against substantial shrinkage.

3. The method of making paper covered veneer which comprises wet steaming a wood veneer ribbon, wetting a face of at least one web of paper, stretching the wet web, applying adhesive to the surface of said stretched web, pressing the adhesived surface of said stretched web against a face of the wet steamed veneer ribbon, heating the assembly to bond the paper to the veneer without materially drying the wood, and thereafter drying the assembly to a moisture content below the shrinkage point of the wood while the paper holds the wood against substantial shrinkage.
